AIR FILTER AND HUMIDIFIER

Clifford A. Mulholland, Tulsa, Okla.

Application September 3, 1935, Serial No. 38,885

8 Claims. (Cl. 261—118)

This invention relates generally to air filters and humidifiers and more specifically to an apparatus of this type which includes the use of streams or bodies of water or other suitable fluid for removing dust and other foreign matter from air being treated while said air is passing along a tortuous path through the apparatus, the predominant object of the invention being to provide an improved apparatus of this type which is capable of performing its intended function in a highly efficient manner.

Fig. 1 is a side elevation of the improved apparatus with portions broken away so as to illustrate in section parts of the structure that would be otherwise concealed.

Fig. 2 is a vertical section taken on line 2—2 of Fig. 1.

In the drawing, wherein is shown for the purpose of illustration, merely, one embodiment of the invention, A designates the improved apparatus generally. The apparatus A includes an outer casing 1 which rests upon suitable supporting elements 2, said casing 1 preferably being of cylindrical form as shown most clearly in Fig. 2.

The outer casing 1 is closed at one of its ends by a wall 3, which preferably, though not necessarily, is formed integral with the cylindrical wall of said outer casing, and at the opposite end of the outer casing the cylindrical wall thereof is provided with an outstanding annular flange 4. The flanged end of the outer casing 1 is closed by an end wall structure 5 which is provided with an annular flange 6 that corresponds in shape and proportions to the flange 4 of the outer casing, and bolts or other suitable fastening devices 7 are extended through apertures formed through the flanges 4 and 6 and through a gasket 9 interposed between said flanges so as to secure the end wall structure 5 to the outer casing in a manner to provide a fluid-tight joint between said parts. At its outer end the end wall structure 5 is provided with an opening that is closed by a removable plate 10 which is secured in place by means of elongated bolts or tie rods 11 extended through the apparatus A as shown most clearly in Fig. 1, the joint between said removable plate and said end wall structure being made fluid-tight through the instrumentality of a gasket 12 which is interposed between said removable plate and a portion of said end wall structure.

Located within the outer housing 1 of the apparatus A is a spirally arranged sheet of material 13 which extends from one to the oppo-

site end of the apparatus so as to provide a continuous spiral air passageway 14 which is closed at its opposite ends by the end wall 3 and the removable plate 10 of the end wall structure 5 of the apparatus. The spirally arranged sheet of material 13 is secured at one of its ends to the cylindrical wall of the outer housing 1 at the point designated by the reference character 15 in Fig. 2, and adjacent to said point of attachment the spirally arranged sheet of material is provided with a curved portion 16 which co-operates with the cylindrical wall of the outer casing in a manner to provide a pocket 17 which, in the operation of the apparatus, is adapted to receive a body of liquid as shown in Fig. 2. At its opposite or inner end the spirally arranged sheet of material 13 terminates in a portion 18 having a curvature of relatively small radius and a portion 19 of said sheet of material is bent outwardly and upwardly as shown in Fig. 2, to provide a substantially V-shaped trough 20. In like manner the portions of the two convolutions of the spirally arranged sheet of material 13 which are arranged immediately above the inner end portion of said sheet of material are shaped to provide substantially V-shaped troughs 21 and 22, the trough 21 being located immediately above and slightly to the right of the trough 20, as shown in Fig. 2, and the trough 22 being located immediately above and slightly to the right of the trough 21, as shown in said view. Perforations 22' are formed through the sheet of material 13 at the bottom portions of the troughs 20, 21 and 22, and similar apertures 24' are formed through the curved portion 16 of the spirally arranged sheet of material at the lower portion of the pocket 17.

As shown in Fig. 2, the lower portions of the convolutions of the spirally arranged sheet of material 13 provide segmental troughs 23, 24 and 25, and the lower portion of the outer casing provides a similar segmental trough 26. As will presently appear herein, the V-shaped troughs 20, 21 and 22, and the segmental troughs 23, 24, 25 and 26, in the operation of the apparatus, receive bodies of fluid, and the portions of the convolutions of the spirally arranged sheet of material are provided with apertures 27 and 27' through which fluid passes from the segmental trough 23 to the segmental trough 24, from the segmental trough 24 to the segmental trough 25, and from the segmental trough 25 to the segmental trough 26. Associated with the segmental trough 26 is a fluid-discharge conductor 27a which is extended through an open-

ing formed through the otherwise imperforate portion of the cylindrical wall of the outer casing which provides the bottom of the segmental trough 26. The conductor 27^a is extended upwardly into the segmental trough 26 and is provided with one or more openings 28 through which fluid may pass from the segmental trough into the conductor 27^a to be conducted from the apparatus to a circulating pump for reintroduction into the apparatus, or to a sewer or other place of disposition.

At the opposite ends of the apparatus air intake conduits 29 are provided through which air to be treated enters the apparatus, these conduits being supported in openings formed through the wall 3 of the outer casing of the apparatus and through the removal plate 10 of the end wall structure 5, respectively. The intake conduits comprise each a tubular element open at its outer end and at the lower portion of its inner end (see Fig. 1) and above the open inner portion of the conduit said tubular element is provided with an angularly disposed portion 30 which serves to direct the incoming air in a downward direction within the apparatus.

The air discharge means of the apparatus comprises an outwardly and upwardly extended structure 31 of rectangular formation which at its base where the structure is attached to the outer casing of the apparatus at an opening formed in the cylindrical wall of said outer casing, is of only slightly less width than the length of said outer casing. From this point the structure 31 converges to a rectangular neck portion 32 of relatively small dimensions, and associated with this rectangular neck portion is a tubular sleeve 33 which provides the air discharge end of the structure 31. In order to distribute air circulation evenly throughout the air discharge structure 31, I arrange vanes 34 within said structure in geometrically spaced relation, as shown in Fig. 1. These vanes extend from the point at which the air discharge structure 31 is attached to the outer casing of the apparatus, to the approximate inner end of the rectangular neck portion 32, and in addition to serving to distribute air circulation within the structure 31 these vanes act as baffles which remove excess moisture from the air passing from the apparatus. At the point where the convergent portion of the air discharge structure 31 joints the rectangular neck portion 32 thereof, upwardly inclined baffles 35 are arranged between the vanes 33 and between the end vanes and the opposite side of the convergent portion of the structure 31. These baffles serve to prevent flow of excess moisture outwardly through the discharge end of the air discharge structure of the apparatus.

Extended longitudinally through the apparatus is a fluid pipe 36 which is provided with perforations 37 at the under side of the portion of said pipe which is located within the apparatus. This pipe is connected to a source of fluid under pressure, such as water from a city water supply, or a separate pump or like means may be employed to pump fluid through the pipe 36, in which event the fluid may be withdrawn from the apparatus by the pump or like means and reintroduced into the apparatus by pumping the fluid into and through the pipe 36. Fluid discharged from the pipe 36 through the perforations 37 thereof passes into the trough 22, from which trough said fluid passes through the apertures 22' into the trough 21. In a like manner the fluid within the trough 21 passes through the

apertures 22' thereof into the trough 20, and from said trough 20 the fluid passes through the apertures 22' of said trough 20 into the segmental trough 23. The fluid within the segmental trough 23 passes through the apertures 21 and 21' at the bottom of said segmental trough into the segmental trough 24, said fluid passing from said segmental trough 24 through the apertures 21 and 21' thereof into the segmental trough 25 and from the segmental trough 25 through its apertures 21 and 21' into the segmental trough 26. From the segmental trough 26 the fluid passes through the openings 28 into the discharge pipe 27^a by which it is conducted from the apparatus. It is important to note that the apertures 22' and 21 and 21' are of such diameter and of such number that bodies of fluid are maintained at all times in the V-shaped troughs 20, 21 and 22, and in the segmental troughs 23, 24, 25 and 26, so that constantly flowing streams of fluid will issue from said apertures.

The improved apparatus operates by creating a difference in pressure at the discharge end of the discharge structure 31 provided by the element 33, as compared with the air intake ends of the elements 29. This causes air to be treated to enter the apparatus and move spirally in a clockwise direction through a series of sprays of fluid and emerge from the air discharge means of the apparatus thoroughly cleaned and moistened. Because of the eccentric arrangement of the convolutions of the sheet 13, the spiral air passageway formed through the apparatus varies in width. This causes the velocity of the air passing through the apparatus to be decreased as said air approaches the water surfaces in the segmental troughs whereby dust particles carried by the air will drop therefrom. The discharge apertures 21 of the segmental troughs 23, 24 and 25 are so located and proportioned as to maintain fluid levels above the apertures and prevent by-passing of air through said apertures. Also these maintained fluid levels provide for the necessary contact between the air being treated and the bodies of fluid in the segmental troughs. The discharge apertures 21' at the lowermost points of the segmental troughs 23, 24 and 25 are fewer in number than the discharge apertures 21 and serve to permit complete drainage of fluid from said segmental troughs when this is desired. Due to the fact that the perforated pipe 36 is separated from the air discharge opening in the outer casing at which the structure 31 is disposed by a turn of the sheet 13, discharge of fluid directly from said perforated pipe to said air discharge opening is prevented. Also excessive moisture that may find its way to the air discharge structure 31 of the apparatus is baffled by the baffles 35 and this excessive moisture flows back into the interior of the apparatus and is conducted to the pocket 17 wherein a body of fluid is accumulated to provide a fluid seal at that point. The discharge apertures at the bottom of the pocket 17 serve to limit the volume of fluid within the pocket.

In constructing one of the improved apparatus, the amount and kind of air to be treated determines the number of turns of the sheet 13. Also in the operation of the apparatus, the desired humidity may be obtained by regulating the supply of fluid. In this connection it is pointed out that water ordinarily will be used when it is desired to humidify the air being treated. However if no humidification of the air is desired, the fluid employed may be a suitable light oil.

I claim:

1. An apparatus of the class described comprising an outer casing having air inlet and air discharge means, an element disposed within said outer casing and arranged spirally about the major axis of said outer casing to provide a spiral air passageway with which said air inlet and discharge means communicate, liquid-receiving troughs arranged within said outer casing, said troughs being arranged one above the other and being so constructed that liquid flows from higher to lower troughs in streams which traverse said air passageway, and means extended into said outer casing for introducing liquid into said troughs. 10
2. An apparatus of the class described comprising an outer casing having air inlet and air discharge means, an element disposed within said outer casing and arranged spirally about the major axis of said outer casing to provide a spiral air passageway with which said air inlet and discharge means communicate, liquid-receiving troughs arranged within said outer casing, said troughs being arranged one above the other and being provided with apertures through which liquid flows from higher to lower troughs in streams which traverse said air passageway, means extended into said outer casing for introducing liquid into said troughs, and means for discharging liquid from within said outer casing. 15
3. An apparatus of the class described comprising an outer casing having air inlet and air discharge means, an element disposed within said outer casing and arranged spirally about the major axis of said outer casing to provide a spiral air passageway with which said air inlet and discharge means communicate, liquid-receiving troughs arranged within said outer casing, said troughs being arranged one above the other and being provided with apertures through which liquid flows from higher to lower troughs in streams which traverse said air passageway, means extended into said outer casing for introducing liquid into said troughs, and means for discharging liquid from within said outer casing. 20
4. An apparatus of the class described comprising an outer casing having air inlet and air discharge means, an element disposed within said outer casing and arranged spirally about the major axis of said outer casing to provide a spiral air passageway with which said air inlet and discharge means communicate, liquid-receiving troughs arranged within said outer casing, said troughs being arranged one above the other and being provided with apertures through which liquid flows from higher to lower troughs in streams which traverse said air passageway, means extended into said outer casing for introducing liquid into said troughs, means for discharging liquid from within said outer casing, and means within said air discharge means for distributing circulation of air therein. 25
5. An apparatus of the class described comprising an outer casing having air inlet and air discharge means, an element disposed within said outer casing and arranged spirally about the major axis of said outer casing to provide a spiral air passageway with which said air inlet and discharge means communicate, liquid-receiving troughs arranged within said outer casing, said troughs being arranged one above the other and being provided with apertures through which liquid flows from higher to lower troughs in streams which traverse said air passageway, and means extended into said outer casing for introducing liquid into said troughs. 30
6. An apparatus of the class described comprising an outer casing having air inlet and air discharge means, an element disposed within said outer casing and arranged spirally about the major axis of said outer casing to provide a spiral air passageway with which said air inlet and discharge means communicate, liquid receiving troughs arranged within said outer casing, said troughs being arranged one above the other and being provided with apertures through which liquid flows from higher to lower troughs in streams which traverse said air passageway, means extended into said outer casing for introducing liquid into said troughs, means for discharging liquid from within said outer casing, means within said air discharge means for distributing circulation of air therein, baffle means for preventing excessive discharge of moisture from said air discharge means, and a pocket for receiving moisture baffled by said baffle means. 35
7. An apparatus of the class described comprising an outer casing having air inlet and air discharge means, an element disposed within said outer casing and arranged spirally about the major axis of said outer casing to provide a spiral air passageway with which said air inlet and discharge means communicate, the convolutions of said spirally arranged element being disposed eccentric with respect to each other whereby the width of said air passageway is varied, liquid-receiving troughs arranged within said outer casing, said troughs being arranged one above the other and being so constructed that liquid flows from higher to lower troughs in streams which traverse said air passageway, and means extended into said outer casing for introducing liquid into said troughs. 40
8. An apparatus of the class described comprising an outer casing having air inlet and air discharge means, an element disposed within said outer casing and arranged spirally about the major axis of said outer casing to provide a spiral air passageway with which said air inlet and discharge means communicate, liquid-receiving troughs arranged within said outer casing, said liquid-receiving troughs being produced by portions of said spirally arranged element, said troughs being arranged one above the other and being so constructed that liquid flows from higher to lower troughs in streams which traverse said air passageway, and means extended into said outer casing for introducing liquid into said troughs. 45
